US0D1086385S

(12) **United States Design Patent** (10) **Patent No.:** **US D1,086,385 S**
(45) **Date of Patent:** **** Jul. 29, 2025**

(54) **FAUCET**

(71) Applicant: **WENZHOU FURUISI BUILDING MATERIALS CO., LTD**, Wenzhou (CN)

(72) Inventor: **Chunhe Qiu**, Wenzhou (CN)

(73) Assignee: **WENZHOU FURUISI BUILDING MATERIALS CO., LTD**, Wenzhou (CN)

(**) Term: **15 Years**

(21) Appl. No.: **29/935,483**

(22) Filed: **Apr. 2, 2024**

Related U.S. Application Data

(63) Continuation-in-part of application No. 29/843,503, filed on Jun. 22, 2022, now Pat. No. Des. 1,056,143.
